(57) **CLAIM**

The ornamental design for an automobile, as shown and described.

DESCRIPTION

FIG. 1 is a front and side perspective view of an automobile showing our new design;

FIG. 2 is a rear and side perspective view thereof;

FIG. 3 is a right side view thereof; the left side view being a mirror image (with the exception of the gas filler cap that is omitted in the left side view);

FIG. 4 is a front view thereof;

FIG. 5 is a rear view thereof; and,

FIG. 6 is a top view thereof.
